Primary Examiner—T. Chase Nelson*Assistant Examiner*—John Windmuller(74) *Attorney, Agent, or Firm*—Dorr, Carson & Birney, P.C.(57) **CLAIM**

The ornamental design for a compact high definition digital television antenna, as shown and described.

DESCRIPTION

Related applications are U.S. patent application Ser. No. 12/474,119 filed May 28, 2009 entitled Compact High Definition Digital Television Antenna and a U.S. Design patent application Ser. No. 29/345,812 filed Oct. 22, 2009 entitled Compact High Definition Television Antenna.

FIG. 1 is a perspective view of a compact high definition digital television antenna showing our new design.

FIG. 2 is a front elevation view thereof.

FIG. 3 is a right side elevation view thereof.

FIG. 4 is a left side elevation view thereof.

FIG. 5 is a top plan view thereof.

FIG. 6 is a bottom plan view thereof; and,

FIG. 7 is a rear elevation view thereof.

Mounting holes are shown in broken lines to depict environmental subject matter only and form no part of the claimed design.
